UNITED STATES PATENT OFFICE.

FREDERICK JAMES DANN, OF COUNTESTHORPE, ENGLAND, ASSIGNOR TO WALLACE JAMES BARTHOLOMEW, OF LONDON, ENGLAND.

SPADE AND LIKE DIGGING-TOOL.

1,353,459.

Specification of Letters Patent. Patented Sept. 21, 1920.

Application filed May 27, 1919. Serial No. 800,148.

To all whom it may concern:

Be it known that I, FREDERICK JAMES DANN, subject of the King of Great Britain, residing at Countesthorpe, in the county of 5 Leicester, England, have invented new and useful Improvements Relating to Spades and like Digging-Tools, of which the following is a specification.

This invention relates to hand operated 10 digging appliances such for example as spades and forks commonly used for gardening purposes and the object of the invention is to construct the same in such a manner as to reduce the amount of bodily 15 exertion required in using the same and the consequent fatigue due to prolonged digging.

The invention is designed to obviate the 20 necessity for lifting the load by bodily raising the instrument after it has been inserted into the ground as in digging operations.

The invention consists in combining with 25 the digging instrument means by which the said instrument is converted into a lever of the first order and by which the load can be raised without bodily lifting the instrument and can also be turned or moved on its fulcrum so as to deliver the load.

The invention comprehends the combination 30 with a digging tool or instrument of a stand or fulcrum movably attached thereto and upon which the tool, after it has been forced into the ground, can be moved to raise the earth thereon and rotated sufficiently to discharge or turn over the load 35 before depositing it upon the ground adjacent to the spot from where it was dug out or lifted.

In order that the invention may be clearly 40 understood and readily carried into practical effect reference is made in further describing the same to the accompanying drawings, wherein,

Figures 1, 2 and 3 illustrate the use of the 45 invention as applied to a fork and show respectively the actions of inserting the fork into the ground, levering up the sod or spit of earth, and the final operation of turning the same over.

Fig. 4 shows one form of stand or fulcrum.

Fig. 5 is a view at right angles to Fig. 4 showing an alternative form of clip.

Figs. 6 and 7 indicate alternative methods

of retaining the clip in position on the shaft 55 of the fork.

Fig. 8 represents another construction of stand or fulcrum.

Fig. 9 shows the upper part of the stand provided with a swiveling head. 60

Throughout the drawings like parts are designated by similar reference characters.

Referring to the drawings it will be seen that the fork is provided with a stand or fulcrum consisting of an upright element 65 or pillar 2 having a base 3 for resting on the ground, such base being extended in one or more directions as shown to permit of the operator's foot being placed thereto to steady it and hold it in position while the 70 digging is performed. The said stand may either be built up of tubular metal column secured to a wooden base as indicated in Fig. 4 or comprise a single casting of aluminium or other light metal or material as 75 shown in Fig. 8.

The upper part of the stand is provided with means to engage the shaft 4 of the tool so as to afford it an approximately universal movement as may be required by the 80 manipulation of the user. Conveniently for this purpose a metal clip 5 is located around the shaft and the two ends of the clip are extended in parallelism so as to constitute two lips 6 which are located in a recess in 85 the upper part of the stand and a bolt 7 is passed through the one side of the stand then through the two lips mentioned and finally through the opposite side of the stand and secured by a threaded nut or 90 equivalent means so that the said clip and tool shaft can be freely moved up and down thereon in lever fashion. This freedom of movement is further enhanced by means of the roller 8 which is preferably grooved 95 peripherally to provide a bearing for the shaft of the tool and is mounted so as to be free to rotate on the center part of the bolt 7 between the lips 6 of the clip as clearly shown in Figs. 4 and 5. 100

The clip is retained in position on the shaft of the tool in such a manner as to allow the latter to be rotated therein to turn over the load after it has been removed or dug up. For this purpose, as shown in 105 Figs. 1, 2 and 3, the shaft 4 of the tool is provided with a screw or equivalent projection 9 which may either be screwed into a

tapped hole in the metal part of the tool or carried by a detachable metal collar secured around the tool shaft. In either case the said screw or projection is adapted to engage a slot 10 in the clip. Instead of slotting the clip however the same effect may be obtained by means of the alternative arrangement shown in Fig. 6 where it will be seen that the clip 5 is loosely retained in 5 position on the shaft 4 of the tool by means of a loop or strap 11 which may be of metal or leather and securely fastened to the said shaft by a pair of screws. In order to avoid the necessity of either slotting the clip or 10 of drilling and tapping the metal part of the tool for the reception of screws the tool shaft 4 may be provided with a detachable metal band 12, see Fig. 7, having ears or lugs 13 between and by which the clip is 15 loosely retained in position on the shaft.

With the object of facilitating the attachment and removal of the stand or fulcrum to and from the tool the clip 5 may as shown in Fig. 5, be made in two parts hinged together at 14 and provided at the free ends with suitable fastening means such as a hinged stud 15 on one part adapted to engage a slotted lug 16 on the other part and to be secured thereto by means of a fly nut 17 20 or the like.

Provision for adjustment in the height of the stand or fulcrum may be made for example by making the pillar or column thereof of telescopic construction.

35 With a view also to provide for increased freedom of movement particularly when turning over the load the upper part or head of the stand through which the bolt 7 passes may be made to swivel as shown in Fig. 9, 40 wherein, 4 is the shaft of the tool, 5 is the clip and 8 the grooved roller.

The tool is used by forcing the acting end into the ground in the usual way as indicated in Fig. 1.

45 Upon the end of the shaft or handle being lowered into the position shown in Fig. 2

to lift the load the stand or fulcrum comes into contact with the ground behind it and thereafter the tool is operated as a lever, the stand forming the fulcrum. Lowering the handle end of the lever raises the spit or earth from the ground and by rotating the shaft in the aforesaid slot 10 in the clip as shown in Fig. 3 the spit or load is discharged.

55

What I claim then is:—

1. An attachment for a digging tool comprising a stand, a clip movably mounted on the stand and adapted to loosely embrace the shaft of the tool, means for retaining said clip in position on said shaft, and an anti-friction device adapted to provide a bearing for the tool in the vicinity of the clip.

60 2. An attachment for a digging tool comprising a stand, a clip pivotally mounted on the stand and adapted to loosely embrace the shaft of the tool, means for retaining said clip in position on said shaft, and a roller mounted in the top of the stand 70 and adapted to form a bearing for the shaft of the tool.

65 3. An attachment for a digging or like tool comprising a stand, and a clip pivotally mounted in the upper end of the stand and adapted to embrace the shaft of the tool and allow rotation of same therein said clip having a slot therein through which a screw may be passed into the shaft of the tool.

75 4. An attachment for a digging tool comprising a stand, a clip pivotally mounted in the upper end of the stand, said clip being made in two parts hinged together and adapted to embrace and fasten about the shaft of the tool and allow rotation of the same therein, a roller mounted in the stand 80 and situated inside the clip to form a bearing for the tool shaft, and means to retain said clip in position on the said shaft.

85 In testimony whereof I have signed my name to this specification.

FREDERICK JAMES DANN.
